(57) **CLAIM**

The ornamental design for a multipurpose golfer's tool, as shown and described.

DESCRIPTION

FIG. 1 is a perspective of the multipurpose golfer's tool. FIG. 2 is an overhead view of the multipurpose golfer's tool. FIG. 3 is an underside view of the multipurpose golfer's tool.

FIG. 4 is a right side elevational view of the multipurpose golfer's tool.

FIG. 5 is a left side elevational view of the multipurpose golfer's tool.

FIG. 6 is a rear view of the multipurpose golfer's tool. FIG. 7 is a front view of the multipurpose golfer's tool; and, FIG. 8 is an exploded perspective view of the multipurpose golfer's tool.

The broken line showing of the golf tee is included for the purpose of illustrating and forms no part of the claimed design.
